UNITED STATES PATENT OFFICE.

JOHN E. McMINN, OF LOUISVILLE, KENTUCKY, ASSIGNOR TO PEERLESS MANUFACTURING COMPANY, OF LOUISVILLE, KENTUCKY, A CORPORATION OF KENTUCKY.

DESIGN FOR HEATER.

Application filed October 10, 1923. Serial No. 7,466. Term of patent 7 years.

To all whom it may concern:

Be it known that I, JOHN E. McMINN, a citizen of the United States, residing at Louisville, in the county of Jefferson and State of Kentucky, have invented a new, original, and ornamental Design for Heaters, of which the following is a specification, reference being had to the accompanying drawing, forming part hereof, wherein the figure is an elevation of a heater exhibiting my new design. I claim:— The ornamental design for heater, as shown.

JOHN E. McMINN.
